UNITED STATES PATENT OFFICE.

HENRY G. VOIGHT, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CONTROLLING MEANS FOR SLIDING CLOSURES.

1,204,913.

Specification of Letters Patent. Patented Nov. 14, 1916.

Application filed August 28, 1913, Serial No. 787,069. Renewed August 12, 1915. Serial No. 45,257.

To all whom it may concern:

Be it known that I, HENRY G. VOIGHT, a citizen of the United States, residing at New Britain, Hartford county, State of Connecticut, have invented certain new and useful Improvements in Controlling Means for Sliding Closures, of which the following is a full, clear, and exact description.

This invention relates to controlling means for sliding closures such as the entrance doors to elevator wells and especially to such controlling means providing arms connecting the door and its casing, which arms, when the door is closed, are arranged to lock the door against opening from the opposite side.

The present invention relates more particularly to controlling means for use in connection with such arms, which controlling means requires but minimum effort to move the arms to unlocked position and to open the door. In addition the structure is designed to provide an apparatus which will be especially useful in connection with doors having glass panels in that the operating mechanism is concealed from view and does not mar the attractive appearance of the doors from the opposite side.

To this end the invention consists in the structure described in detail in the following specification, taken in connection with the accompanying drawings forming part thereof and illustrating a preferable embodiment of the invention.

In these drawings, Figure 1 is a view in front elevation and from the interior of the elevator well showing the embodiment of the present invention in a door controlling means such as described. Fig. 2 is a fragmentary view, in front elevation and on an enlarged scale, of the forward edge of the door showing the controlling handle and its connections applied thereto. Fig. 3 is a vertical section on the line 3—3 of Fig. 2. Fig. 4 is a transverse section on the line 4—4 of Fig. 2. Figs. 5, 6 and 7 are views of details of structure.

Referring to the drawings by numerals: 1 designates the frame of a sliding door and 2 the door casing. The door shown is of the type provided with glass panels 4 divided by opaque transverse strips 3. Secured to the door casing 2 or other relatively stationary abutment, is a bracket plate 5 to the lower end of which is pivotally secured the arm 6 of a power cylinder 7. An arm 10 has its rear end pivotally secured to said bracket plate adjacent its upper end and is provided adjacent said pivoted end with a transverse arm 9 to which the piston rod 8 of the power cylinder is pivotally connected. The free end of the arm 10 is pivotally secured to the rear end of a second arm 11 whose forward end is pivotally mounted upon a plate 12 which constitutes a movable abutment and is secured to the door frame 1 at the forward edge of the door. The plate 12 is preferably provided with a boss 13 having a stud 14 formed thereon upon which the end of the arm 11 is journaled. The two arms described form a toggle and with the plates 5 and 12 are positioned preferably so that the arm 11 will extend across the door in the plane of the transverse partitioning strip 3 so that with the door closed, the arm 11 will be hidden from view. This power cylinder 7, through its connection with the transverse arm of the toggle arm 10 normally tends to swing said arm, and through it, arm 11 in a direction to move the door to closed position. The components of the two arms are so figured that when the door is in closed position, the pivot points of these arms are in horizontal alignment so that a dead center lock is provided against opening movement on the part of these arms. The specific construction of the power cylinder is immaterial as far as the purposes of the present invention are concerned. One form of construction which the power cylinder may assume is shown in my prior Patent No. 1,028,833.

In order to move the sliding door to open position against the force of the power

cylinder, means must be provided for first breaking the dead center lock of the toggle arms. In the present invention I provide means for breaking this lock and for opening the door, which means, in door closed position, is positioned in the plane of the opaque door frame and thereby concealed from view from the opposite side of the door. This operating means is preferably 5 constructed as follows: The plate 12, secured to the forward edge of the door frame, is provided with a stud 15 at a point below the boss 13, which stud has its end reduced in diameter as at 16 to provide a bearing upon 10 which is journaled the upper end 17^a of an operating handle 17. This handle adjacent its lower end is provided with an offset 18 affording a hand grip for the operator. At its upper pivoted end the operating handle 15 is provided with an integral right angle extension 19 offset from the plane of the main body of the handle. At a point in alinement with the vertical arm 19^a of this extension, spaced links 20 are pivotally 20 secured to the arm 11 of the toggle adjacent its point of pivotal connection to the door. These spaced links are secured to the opposite faces of the toggle arm and extend 25 downwardly, embracing therebetween the vertical portion 19^a of the handle extension, the lower end of which portion is pivotally mounted between said links as at 21. The length of the operating handle 17 is much 30 greater in proportion to the length of the links 20 and of the arm 19^a of its extension so that a powerful operating leverage is afforded against the toggle arm 11. It will be evident, therefore, that when the operator grasps the operating handle and 35 swings it away from the forward edge of the door and relative to the door and to the toggle, the toggle arm 11, through links 20, will be moved upwardly to break the horizontal alinement of the toggle arms so that 40 the door may be moved to open position by a continued pull on the handle in the same direction, the powerful leverage secured through handle 17 swinging the toggle arms upwardly and moving the door toward open 45 position and against the force of the closer cylinder: This movement is accomplished with rapidity because of the action of the operating handle against toggle arm 11 at a point adjacent its pivoted end. When the 50 handle is released, the power of the closer cylinder will swing the arms downwardly and in a direction to move the door to closed position, the operating handle and its connections to the toggle returning to the position shown in full lines in Figs. 1 and 2. The operating handle described provides a 55 powerful leverage against the toggle arm 11 by reason of the compounding of the leverage through its arm 19^a and links 20

so that the toggle lock may be broken and 65 the door opened quickly with a minimum effort on the part of the operator. At the same time, these connections are so arranged 70 that they are invisible from the opposite side of the door in case a glass panel is provided, the invention combining effectiveness of operation with concealment of the operating parts.

While I have herein described a particular and specific embodiment of the invention, 75 it will be understood, of course, that the same may be varied in structure and relative arrangement of parts within the spirit of the invention and the scope of the appended claims.

What I claim, therefore, and desire to 80 secure by Letters Patent, is:

1. Controlling means for sliding doors comprising a pair of connected toggle levers, a stationary abutment for the free end of 85 one of said levers, a movable abutment for the other lever comprising a pivot upon which the free end of the last mentioned toggle lever is mounted, another pivot on 90 said abutment below the first mentioned pivot, an operating handle mounted thereon, a laterally extending arm on the operating handle, an upwardly projecting coupling link pivotally mounted upon said extension 95 and operatively connected with the last mentioned toggle link between its ends to buckle said toggles by the upward movement of said coupling link.

2. Controlling means for sliding doors comprising a pair of connected toggle levers, 100 a stationary abutment for the free end of one of said levers, a movable abutment for the other lever comprising a pivot upon which the free end of the last mentioned toggle lever is mounted, another pivot on said 105 abutment below the first mentioned pivot, an operating handle mounted thereon, a laterally extending arm on the operating handle, an upwardly projecting coupling link pivotally mounted upon said extension 110 and operatively connected with the last mentioned toggle link between its ends to buckle said toggles by the upward movement of said coupling link, said handle extension projecting outwardly and downwardly, said coupling link being connected 115 to the lower part of said extension.

3. Controlling means for sliding doors comprising a pair of connected toggle levers, a stationary abutment for the free end of 120 one of said levers, a movable abutment for the other lever comprising a pivot upon which the free end of the last mentioned toggle lever is mounted, another pivot on 125 said abutment below the first mentioned pivot, an operating handle pivotally mounted thereon, a laterally extending arm on the operating handle, an upwardly projecting

coupling link pivotally mounted upon said extension and operatively connected with

the last mentioned toggle link between its ends to buckle said toggles by the upward

5 movement of said coupling link, the pivotal connection between said coupling link and said handle being below the pivotal mount-

ing of said handle on said movable abutment.

HENRY G. VOIGHT.
